GOLF CLUB HEAD

Edward A. Pavlis, Chicago, Ill., assignor to National Die Casting Company, Chicago, Ill., a corporation of Illinois

Application May 9, 1956, Serial No. 41,411

Term of patent 14 years

(Cl. D34—5)

Fig. 1

Fig. 2.

Fig. 3.

Fig. 4.

Fig. 1 is a top view of a golf club head embodying my new design;

Fig. 2 is a rear elevational view of the club head of Fig. 1;

Fig. 3 is an elevational view of the toe end of the golf club head of Fig. 1; and

Fig. 4 is a perspective view of the toe end of the club head of Fig. 1.

I claim:

The ornamental design for a golf club head, substantially as shown.
